UNITED STATES PATENT OFFICE.

JOHN P. KING, OF PROVIDENCE, RHODE ISLAND, ASSIGNOR, BY DIRECT AND MESNE ASSIGNMENTS, TO IDEAL BRAIDING MACHINE COMPANY, A CORPORATION OF RHODE ISLAND.

DRIVING MECHANISM FOR BRAIDING MACHINES.

Application filed March 16, 1922, Serial No. 544,263. Renewed February 29, 1924.

To all whom it may concern:

Be it known that I, JOHN P. KING, a citizen of the United States, residing at Providence, in the county of Providence and State 5 of Rhode Island, have invented certain new and useful Improvements in Driving Mechanism for Braiding Machines, of which the following is a specification.

This invention relates to driving mechanism 10 for braiding machines and is an improvement on my co-pending application Serial No. 397,238, filed July 19, 1920.

This invention has for its object to provide means in the driving mechanism where- 15 by the machine may be started gradually to prevent undue shocks and jars to the mechanism, and stopped quickly to prevent the forming of imperfect work by continuing the braiding action after the thread is 20 broken, and to arrest the carrier requiring attention in a position most accessible to the attendant for piecing up the thread or for doffing and replacing with a fresh bobbin.

A further object of the invention is to 25 provide a stop motion for controlling the driving mechanism, which is very delicate and sensitive in its operation and which may be engaged by the carrier with a wedg- 30 ing action thus eliminating the shock or jar on the mechanism, which might be caused if the rapidly running carrier brought up against the stop motion operating lever with a positive or direct engage- 35 ment.

With these and other objects in view, the invention consists of certain novel features of construction, as will be more fully de- 40 scribed, and particularly pointed out in the appended claims.

In the accompanying drawings:

Figure 1 is a top view showing a portion of a machine with my improved stopping mechanism attached thereto.

Figure 2 is a side elevation partly in sec- 45 tion showing my improved lever-retaining latch and the means for tripping the same.

Figure 3 is a sectional side elevation of the clutch and brake portion of the driving mechanism.

It is found in practice very desirable to 50 provide a stop motion for high-speed braiding machines in which the stopping mechanism may be tripped by a passing carrier having a defective thread supply and to

construct this mechanism so that it will be 55 positive and yet delicate in its action to withdraw the latch bolt and permit the operating lever to move and separate the clutch members and simultaneously apply a friction brake to the carrier driving mech- 60 anism and to so nicely control the stopping of the carriers that they will move but a very short distance after the tripper has been engaged. By this construction many 65 advantages are obtained among others being first, that the carrier with a defective supply is caused to stop in front of the attendant to receive immediate attention and by stopping quickly the thread of the exhausted cop 70 is not drawn out sufficiently to unthread the carrier thus permitting this end to be tied to that of a fresh bobbin and so obviate the necessity of threading up. Then again where the carrier is stopped quickly the 75 braiding of the broken end into the work is prevented, and the following is a detailed description of one means by which these advantages may be accomplished:—

With reference to the drawings, 10 designates the raceway-table of my improved 80 braiding machine in which the raceways 11 are shown. A portion of one of the usual carrier driving gears 12 is indicated in dotted lines as meshing with the main carrier driving gear 13 by which the carriers 85 are driven through their raceways in the usual way.

This main driving gear 13 is mounted on the upright shaft 14 and motion is trans- 90 mitted to this shaft from a main drive shaft 15 through the beveled gears 16 and 17, the latter being provided with a tapering friction clutch face 18 adapted to be engaged by the opposite corresponding clutch mem- 95 ber 19 which latter is keyed at 20 to the shaft 14 and a spring 21 is positioned be- 100 tween the two clutch members to separate them when released by the operating lever 22, which lever is pivoted at 23, and its lower forked end 24 is arranged to engage the under side of the clutch member 19 through the ball-bearing plates 25.

This lever 22 extends upwardly on an angle and is provided near its upper end with an adjustable latch-engaging member 105 and also with an operating handle 27.

In order to control the releasing of this handle to permit the disengaging of the

clutch members, I have provided a latch bolt 28 mounted to slide endways in the bearing arm 29 being normally pressed outwardly by a spring 30 and in this latch bolt 5 I have mounted a transversely-disposed pin 31 which slides in the slots 32 in this bearing member 29 with the bolt thereby preventing rotation of the bolt in its bearing and maintaining its notched engaging face 10 33 in position to accurately engage the member 26 on the lever.

The outer face of this bolt is preferably beveled as at 34 and the under face 35 of the bolt-engaging member 26 is also beveled 15 whereby a forward swinging motion of the lever 22 after having been tripped serves to force the bolt inwardly to permit the member 26 to snap past its end and be engaged by the bolt to hold the lever in operative position.

In order to control the action of this latch bolt to withdraw it when the supply on the carrier is defective, that is when the supply is exhausted or the thread broken 25 permitting the bottom weight 43 to drop, I have provided a three-arm lever 36 pivotally mounted on the pin 37, one of the arms 38 extending into proximity to one portion of the raceway while another arm 39 extends 30 into proximity of another portion of the raceway while the third arm 40 extends forward and has a cross-bar at its end. This bar is provided at its outer ends with downwardly-extending pins 41 provided with 35 rollers 42 to engage the transverse latch bolt pin 31.

It will be noted that the ends of the arms 38 and 39 have upturned flanges 44 and 45, respectively, which flanges are set on an 40 angle to the travel of the carrier whereby the engaging edge of the bottom weight 43 will strike this flange a glancing blow and by a wedging action, force the lever to swing by an easy motion, and without the shock 45 which would be due to a direct engagement with a lever set at right angles to its travel. This easy swinging movement of the lever is transmitted through the arm 40 to the rollers 42 to engage the transverse pin 31 50 in the latch to move the bolt back to release the lever 23 which then under action of the spring 21, see Figure 3, separates the clutch parts to release the carrier-driving mechanism. At the same time the lower 55 clutch part drops into engagement with the fixed leather friction surface 46 thereby providing a brake against which this clutch part 19 is pressed by the spring 21 thereby promptly arresting the action of the braiding mechanism and that without shock or jar to the same.

By my improved construction I have obtained a number of important advantages 60 which are essential in a high-speed braiding machine particularly when producing

cord for the manipulation of automobile tire casings or other high grade or particular work: First, the machine may be stopped at once and without shock or jar to the mechanism; second, when the stop motion is operated the clutch instantly ceases to drive, and a brake is immediately and automatically applied to arrest further travel of the carriers and so prevents the braiding of defective work; third, by my improved mechanism the carrier with a defective thread is itself arrested at the front of the machine where it is most accessible to the operator for piecing up or for replacing the exhausted bobbin with a fresh one.

By stopping the machine at once the waste to the finished product is reduced to a minimum as in producing braided material for very high class work, all the imperfections must be cut out and the braid pieced up and 85 the piecing-up of such stock reduces its market value.

My improved device is very simple in construction and effective in its operation and by its use a braiding machine may be run 90 at a very high speed and the loss by overrunning and the consequent production of imperfect work, is reduced to the minimum.

The foregoing description is directed solely towards the construction illustrated, but 95 I desire it to be understood that I reserve the privilege of resorting to all the mechanical changes to which the device is susceptible, the invention being defined and limited only by the terms of the appended claims.

I claim:

1. In a braiding machine the combination with a raceway-table, of a friction clutch through which the driving of the carriers in said raceway is controlled, a lever for operating said clutch, an arm pivotally mounted adjacent the raceway in said table to be engaged by a carrier traveling therein having a defective thread supply, and a latch bolt positioned to retain said lever in operative position and adapted to be withdrawn by a movement of said arm to release said lever and permit said clutch to operate.

2. In a braiding machine the combination with a raceway-table, of a friction clutch through which the driving of the carriers in said raceway is controlled, a lever for operating said clutch, an arm pivotally mounted adjacent the raceway in said table to be engaged by a carrier traveling therein having a defective thread supply, a spring-pressed latch-bolt positioned to retain said lever in operative position, and means whereby a swinging movement of said arm will withdraw said bolt to release the lever and permit the clutch to operate.

3. In a braiding machine the combination with a raceway-table, of a friction clutch through which the driving of the carriers in said raceways is controlled, a lever

through which the clutch parts are retained in engaging position, a spring for separating the clutch parts when released, an arm pivotally mounted adjacent the raceway on 5 said table to be engaged by a traveling carrier having a defective thread supply, a latch bolt, means in said lever for engaging said latch to hold the clutch parts in engagement, and means for adjusting said latch engaging 10 means to control the pressure of the driving engagement of the clutch members.

4. In a braiding machine the combination with a raceway-table, of a friction clutch through which the driving of the carriers 15 in said raceways is controlled, a lever through which the clutch parts are retained in engaging position, a spring for separating the clutch parts when released, an arm pivotally mounted adjacent the raceway on 20 said table to be engaged by a traveling carrier having a defective thread supply, a spring pressed latch bolt positioned to retain said lever in operative position, and means whereby a swinging movement of said arm 25 will withdraw said bolt to release the lever and permit the disengagement of the clutch parts, and means for automatically applying a brake to the mechanism when the clutch is released.

5. In a braiding machine, the combination with a raceway table, of a friction clutch through which the driving of the carriers in said raceway is controlled, a lever for operating said clutch, an arm pivotally mounted adjacent the raceway in said table to be 30 engaged by a carrier traveling therein having a defective thread supply, a spring pressed latch bolt set to retain said lever in operative position, a transverse engaging 35 pin in said bolt, a transverse bar adjacent the end of said arm, and means on said arm for engaging said bolt pin whereby a swinging movement of said arm will operate through said pin to withdraw the bolt to release the lever and permit the clutch to operate.

6. In a braiding machine the combination

with a raceway-table and carrier drivers, of a friction clutch through which power is transmitted to said drivers, a clutch operating lever, a spring-pressed latch bolt, a latch engaging member on said lever adapted to be adjusted to determine the degree of engaging pressure of the clutch member, and means whereby a passing carrier may be 55 caused to trip said latch and release said clutch to stop the machine.

7. In a braiding machine the combination with a carrier raceway-table and carrier drivers, of a clutch including a spring operated driving part through which power is transmitted to said drivers, an operating lever for moving said clutch parts into effective driving engagement, arms pivotally mounted adjacent the raceway in said table 60 to be engaged by a carrier in the raceway having a defective supply of thread, a latch positioned to engage a member on said lever to maintain said lever in operative position and said latch being adapted to be operated 65 by said arms to disengage said lever and permit said clutch parts to separate, and means for adjusting said latch engaging member.

8. In a braiding machine the combination with a carrier raceway-table and carrier drivers, of a clutch including a spring operated driving part through which power is transmitted to said drivers, an operating lever for moving said clutch part into effective driving engagement, arms pivotally 70 mounted adjacent the raceway in said table to be engaged by a wedging action by a carrier in the raceway having a defective supply of thread, a sliding bolt positioned to maintain said lever in operative position and 75 connected with said arms to be affected by the movement of the latter for disengaging said lever and permitting said clutch parts to separate, and a friction surface against which one of said clutch parts is thrust by 80 the separating spring thereof for arresting the movement of said carrier drivers.

In testimony whereof I affix my signature.
JOHN P. KING.
